FAN

Raymond Médard Hermann François Cockelaere,
Brussels, Belgium

Application July 2, 1953, Serial No. 25,779

Term of patent 14 years

(Cl. D26—7)

FIG. 1

FIG. 2

FIG. 3

To all whom it may concern.

Be it known that I, Raymond Médard Hermann François Cockelaere, a subject of Belgium, residing at Brussels, Belgium, have invented a new, original, and ornamental Design for a Fan, of which the following is a specification, reference being had to the accompanying drawing, forming part thereof.

Fig. 1 is a perspective view of a fan showing my new design.

Fig. 2 is another perspective view of the fan.

Fig. 3 shows an elevational view of the fan.

The rear surface not shown is substantially plain.

I claim:

The ornamental design for a fan, as shown and described.
